UNITED STATES PATENT OFFICE.

ROBERT DAVID MAYO, OF CLEVELAND, OHIO.

COMBINED TOOTHBRUSH AND WATER-GLASS HOLDER.

Application filed April 20, 1921. Serial No. 462,834.

To all whom it may concern:

Be it known that I, ROBERT DAVID MAYO, a citizen of the United States, and a resident of Cleveland, county of Cuyahoga, State of Ohio, have invented certain new and useful Improvements in Combined Toothbrush and Water-Glass Holders, of which the following is a specification.

This invention relates to a combined tooth brush and water-glass holder for household use and is especially concerned with such a holder in which several tooth brushes may be accommodated and protected from dust and the like.

15 One object of the invention is to provide a combined tooth brush and water-glass holder which may be constructed of glass, porcelain, earthenware, enameled metal or other suitable material at small cost.

20 Another object is to provide a sanitary holder of the class described which may be easily and quickly assembled or disassembled or removed from its support for the purpose of cleansing, replacement of parts or other purposes.

25 Another object is to provide an article of the class described with a simple means of attachment to a support.

Another object is to construct the water-glass retaining band for an article of the class described which may be maintained in its proper position at all times.

Other objects will appear and be pointed out in the following specification.

35 Referring to the drawings attached to and forming a part of this specification;

Figure 1 is a front elevation of the device completely assembled;

Fig. 2 is a vertical section taken on line 40 2-2 of Fig. 1;

Fig. 3 is a sectional view taken on line 3-3 thru the tooth brush containing compartment;

Fig. 4 is an enlarged detail view of the 45 back plate showing an opening in which the glass retaining band is secured;

Fig. 5 shows in perspective an end of the glass retaining member;

Fig. 6 is an enlarged fragmentary section 50 taken on line 6-6 of Fig. 1 showing the means of securing the cover of the tooth brush compartment to the back plate; and

Fig. 7 shows a modified form of back plate and means for attachment of the glass retaining band thereto.

A preferred form of my invention is illustrated in the appended drawings in which 1 indicates a back plate, composed of glass, porcelain, enameled sheet iron or other suitable material. Thru opposite corners of plate 1 are apertures 2, adapted to receive the ends of the spring water-glass retaining band 3 and having enlargements conforming to the crimped edges 4 of band 3. These edges preferably stop short of the end of the band, leaving bent portions 5 which can be passed thru apertures 2 and will lie flat against the back of plate 1. Edges 4, seating the apertures, serve to prevent vertical displacement of band 3 when a water-glass (not shown) is inserted or removed.

A shelf 6 is located below band 3 and serves to support a water-glass. It is provided with key hole slots 7 of such size as to permit removal from screws 7^a, which are affixed to a supporting member such as a back board or wall, by simply lifting the shelf vertically until the heads of the screws enter the enlarged portions of the slots and then moving it horizontally away from the screws.

It will be apparent that shelf 6 also provides an adequate means for attaching plate 1 to the supporting member. Screw holes 7^b in the back plate are larger than the head of screws 7^a and may be passed thereover easily. When shelf 6 is then pressed against back plate 1 and screws 7^a take the position in slots 7, as shown in Fig. 1, the back plate is firmly secured to its supporting member.

Below shelf 6 is a series of compartments each one of which is adapted to receive and support a tooth brush. These compartments are formed by upstanding ribs 9 integral with back plate 1. Preferably the ribs include a crosswise rib 9^a integral with the longitudinal ribs adjacent their upper end to form a top wall for the compartments.

Lateral flanges 10, on the lower ends of ribs 9, serve to retain the tooth brushes in the compartments.

To prevent the entry of dust, and similar foreign substances into the compartments where it may collect on the brushes contained therein, a detachable cover 11 is pivotally mounted between extensions 10 of ribs 9 so as to enclose the compartments.

A spring rod 13, having pointed ends, seats in depressions 14 in extensions 12 of ribs 9 and acts as a support for cover 11.

This rod may be formed with a V-shaped loop or other offset intermediate its ends to permit withdrawal of the ends from recesses 14 by a slight springing action.

5. In Fig. 7 a modified construction is shown. Instead of apertures 2 passing thru the back plate 1, a recess or aperture 15 is formed in upstanding side ribs 16 to receive ends 5 of band 3. Recesses 17 in the ribs 16 conform to and accommodate crimped edges 4 of band 3 and assist in maintaining the band in its normal position.

It is evident that my improved device 15 is capable of both easy and quick removal from its supporting member, and a rapid disassembly and assembly of the various parts for purposes of cleansing, replacement of broken or damaged parts, and for other 20 purposes. Vertical and then horizontal movement of shelf 6 permits removal of plate 1 from its supporting member, while a compressing force exerted on band 3 and also on rod 13 will disengage each from 25 their respective seating apertures or recesses.

Altho I have described in detail one device embodying my invention for purposes of illustration, I do not wish to be understood as limiting myself to the specific details set forth. The scope of my invention 30 is defined by what is claimed.

What is claimed:

1. In a combined tooth brush and water 35 glass holder in combination, a back plate having ribs forming a compartment adapted to receive a tooth brush, a cover for said compartment, and means comprising a shelf provided with retainer apertures 40 for detachably securing the said back plate to a supporting member.

2. In a combined tooth brush and wa-

ter glass holder in combination a back plate, upstanding ribs integral with the plate and arranged longitudinally and 45 crosswise thereof to form a plurality of compartments each adapted to receive a toothbrush, a cover for said compartments detachably secured to certain of the said ribs and means for attaching the said plate 50 to a supporting member comprising a shelf provided with key hole screw engaging slots.

3. In a combined tooth brush and water glass holder in combination a back plate having apertures adjacent one end, a spring band having end portions adapted to enter the said apertures, and a shelf located below the said band and adapted to support a water glass retained thereby, the 60 shelf being provided with means comprising keyhole screw engaging slots to secure the back plate to a supporting member.

4. In a combined tooth brush and water glass holder in combination a back plate, 65 a spring band having crimped side edges terminating short of the end thereof, apertures in the plate having enlarged portions conforming to the said crimped edges and adapted to receive the said spring band, 70 and a detachable shelf connected to the back plate below the said band.

5. In a combined tooth brush and water glass holder in combination, a back plate, 75 having a tooth brush receiving compartment, a cover for said compartment, a water glass retaining band, and a shelf adapted to cooperate with the said band to support a water glass and having openings 80 adapted to cooperate in securing the said back plate to a supporting member.

In testimony whereof I affix my signature.

ROBERT DAVID MAYO.
